CLAIM

The ornamental design for a cooler, as shown and described.

DESCRIPTION

FIG. 1 is a front perspective view of a cooler, showing my new design;

FIG. 2 is a rear perspective view of the cooler shown in FIG. 1;

FIG. 3 is a front view of the cooler shown in FIG. 1;

FIG. 4 is a right side view of the cooler shown in FIG. 1;

FIG. 5 is a rear view of the cooler shown in FIG. 1;

FIG. 6 is a left side view of a cooler shown in FIG. 1;

FIG. 7 is a top view of the cooler as shown in FIG. 1; and,

FIG. 8 is a bottom view of the cooler shown in FIG. 1.

The broken lines in the figures illustrate the portions of the cooler and form no part of the claimed design.

1 Claim, 8 Drawing Sheets
